UNITED STATES PATENT OFFICE.

ONOFRIO ABRUZZO, ST. MARGHERITA, SICILY, ITALY.

IMPROVEMENT IN AERIAL CARS.

Specification forming part of Letters Patent No. **80,107**, dated July 21, 1868; antedated July 15, 1868.

To all whom it may concern:

Be it known that I, ONOFRIO ABRUZZO, of St. Margherita, of the Province of Girgenti in Sicily, and Kingdom of Italy, have invented new and useful Improvements in Aerial Navigation; and I do hereby declare the following to be a clear and exact description thereof, sufficient to enable others skilled in the art to which my invention appertains to fully understand and use the same, reference being had to the accompanying drawings, making part of this specification, in which—

Figure 1 is a side elevation of the device illustrating my invention. Fig. 2 is a top or plan view thereof. Fig. 3 is a side elevation of an additional device on the same principle as Fig. 1.

Similar letters of reference indicate corresponding parts in the several figures.

My invention relates to a mode of aerial navigation; and it consists in the peculiar shape of the body of the balloon; also, in the application of forcing and exhausting pumps to the said body; also, in the application of a propeller and rockets or equivalents thereto; also, in wings or paddles having suitable valves, whereby the balloon is properly elevated and guided in any direction, the bursting of its body is prevented, resistance is overcome, and friction avoided.

In the drawings, A represents the body of the balloon, of conical form, or of the form of a spindle, or "cigar-shaped." I desire to construct the same of light sheet-iron; but it may be formed in part of iron and oil-silk, which latter is to be protected by suitable bars or strips extending from the stern to the metal part of the bow or point, whereby the silk part will retain its proper form, and bursting thereof by collision will in a great measure be prevented; but it is desirable to construct it entirely of sheet metal.

To one side of the body I attach or secure a reservoir, B, on which are mounted two pumps, a b, having the usual cylinders, pistons, rods, and operating levers and valves. Pipes c d are connected to the pumps and communicate with interior of the body A. One pump will force the gas or suitable fluid into the body, and the other will exhaust or withdraw the

fluid therefrom. It will be noticed that when the internal pressure becomes too great and dangerous the proper quantity of the fluid must be exhausted from the body by the proper pump, and the reservoir B will receive it. On the other hand, when the body requires its supply of fluid, it can be readily obtained from the reservoir by means of the forcing-pump. The pipes are provided with a manometer to compensate and equilibrate the external pressure of air, which is indicated by an ordinary barometer.

The rear of the body A is formed into a compartment or chamber, C, provided with suitable windows, and is intended for the pilot or necessary workmen. This apartment is to be constructed of sheet-iron, and has a division-wall between itself and the body A.

In the rear of the body I apply a screw-propeller, D, mounted on crank-shaft e, having its bearings in suitable boxes or ears attached to the body. This propeller may be operated by any suitable power through the means of its crank, pitman, or shafts, and pistons from the steam-cylinder f, which is supported on a car or boat, E, suspended from the body of the balloon. Any proper motor may be applied to the propeller.

The car or boat E is to be made of net-work of suitable material, and of a pointed and rounded end, so as to conform in a measure with the forward part of the body. By the peculiar shape of the body its surface offers the least possible resistance, which is therefore overcome and friction is avoided, which advantages are of the utmost importance to the unimpeded flight of the balloon.

The position of the propeller may be varied. Instead of being at the rear, it may be placed under the body A; but I do not limit myself to location, further than that the propeller will be properly mounted so as to propel the balloon when desired.

From the under side of the body A there are suspended wings or paddles F, which are intended to be of scoop form, and attached to arms which pass through the boat E, and are pivoted to lugs or ears on the body A. One side, by preference the rear, is cut out in several places, making openings, which are covered by

valves *g*. The valves will be open when the wings make their forward motion, and I thus overcome the resistance of air against the wings and prevent the checking of the motion of the balloon. When the wings return, the valves close. The wings thus act with full power against the air and impart corresponding motion to the balloon. The wings are to be operated by means of a single rod, which shall connect the two arms of the wings, having a common piston-head which moves in a cylinder, *h*, which is secured to the body or resting on car *E*, or in any proper position.

In lieu of applying both wings to the under side of the body, they may be placed as shown in Fig. 2, or one or more may be applied on the upper side of the body to correspond with those shown in Fig. 1. When the wings are applied as shown in Fig. 2, it is desirable that they should be inclined sidewise, so as to elevate as well as propel the balloon. The wings may be variously applied, however, and I therefore do not limit myself to the position thereof.

The car or boat *E* may contain the necessary workmen, besides passengers, food, baggage, &c. Should it be found necessary to provide more accommodations therefor, an additional car, *G*, may be suspended from the body or car *E*, which shall correspond with each other.

A suitable tiller is applied to the body, either above or below, or at the bow or rear of the body.

H represents a rocket-chamber, which consists of a tube with a breech plug or piece at its rear for placing a war-rocket within the chamber. To its forward end is secured a network frame, *H'*, of conical form, or with a flaring mouth. The object of the application of this rocket is to propel the balloon by the reaction of the elasticity of the air. The network will prevent the fire of the rocket from reaching the other parts of the balloon, and acts on the principle of the safety-lamp. The chamber is mounted on pivots and has free motion horizontally to guide the balloon, and therefore performs the functions of the rudder or tiller. The chamber must be of proper size, as also the rockets, whose power should be known to those who apply them. More than one rocket-chamber may be employed, and they may be arranged at various angles to each other, so as to communicate with each other, and so soon as one rocket is ignited and discharged the next one will follow, and so on throughout.

The propeller may have a rudder or tiller attached to it; or it may be so constructed as to move in a horizontal plane in either direction, and thus direct the balloon. The screw-propeller must be worked in such a manner that its rapid revolution, imparted by a quick engine, will insure the normal power necessary to propel the aerial ship, which normal power is the result of the pressure of the revolving

propeller, combined with the reaction of the air. Wind is nothing but a motion of air toward a body, and if a body moves toward the air the same result is attained. The amount of motion indicates the strength of the wind, and the rapidity of revolution of the propeller gives the power of action and the reaction of the air in the normal power of propulsion. To determine the power of the propeller, then, the diameter of the same, its angle, and the rapidity of its revolution must be calculated, which, if correctly done, will give the precise power attainable.

It will be understood that when the wings *F* are used the propeller and rockets are unnecessary. The propeller may be used without the wings or rockets. The rockets may be used alone, the propeller and wings being then unnecessary.

The various parts are to be put in operation separately whenever desired; but should it be found necessary to employ them simultaneously, it can readily be done by applying power thereto.

Fig. 3 represents an additional device, consisting of a parachute, *A'*, having a slightly inclined handle, and an ordinary car or boat, *E*, which carries a piston-cylinder, *f*, and gives motion to a propeller through the medium of the crank-shaft *e*. This device may be attached to the body *A*, and will elevate it without further appliances. The parachute, as shown, will also elevate itself without the balloon. A large screw or spiral flange, *D'*, is attached to the crank-shaft, and is the raising medium. The rocket *H* may be applied in lieu of the screw, but on the opposite side. A parachute will descend quite slowly, and if the screw is rapidly rotated it is evident that its motion will overcome the gravity of the parachute and elevate it immediately. This acts on the same principle as the screw-propeller, but reversed in its position. The body of the parachute is slightly inclined backward, and will allow the air to act against its under side, and thus catch it. When the screw is put in motion, the device will raise itself, and continue so until a descent is desired.

My device is practical, and is intended to be a useful and quick means for transportation.

Having thus described my invention, what I claim as new, and desire to secure by Letters Patent, is—

1. The reservoir *B* and pumps *a b*, arranged in relation to the body *A*, so as to increase or decrease the pressure of gas therein, all substantially as and for the purpose described.

2. In arrangement with the car and safety-rocket discharge, the propeller *D*, mounted on crank-shaft *e* and applied to the body *A*, substantially as and for the purpose described.

3. In combination with the balloon, a breech-loading rocket-chamber attachment with safety-guard, substantially as and for the purpose described.

4. The wings or oars F, having valves g, operated by the engine, all substantially as described, for the purpose described.
5. The combination of the conical or acutely-formed body A, propeller D, rocket-chamber H, and wings F, substantially as described and for the purpose specified.
6. An inclined parachute arranged to co-op-

erate with the screw or rocket, as and for the purpose described.

To the above specification I have signed my name this 14th day of September, 1867.

ONOFRIO ABBRUZZO.
